GARMENT

Harry Miller, Amsterdam, N. Y.

Application September 12, 1940, Serial No. 356,475

4 Claims. (Cl. 2-98)

My invention particularly relates to a collar for a garment such, for example, as an overcoat which is designed to afford substantially complete protection to the ears of the wearer thereof in cold weather.

Ordinarily, the collars on overcoats are of insufficient width, or height when upstanding, to afford adequate protection to the ears in cold weather since it is customary to make collars comparatively narrow in order that they may have a neat appearance when overfolded.

Broadly speaking, it is an object of my invention to provide a collar of the customary width for a garment or overcoat which may be overfolded in the usual manner to provide the desired neat appearance but which may be upturned and arranged to provide substantially complete protection to the ears of the wearer.

More particularly, it is an object of my invention to provide a collar which is substantially of uniform thickness throughout and therefore may be neatly overfolded and worn in this manner under ordinary weather conditions but which may be upturned and comprises a flap adapted to be extended to overlie the ears.

I attain the foregoing objects by the novel constructions and arrangements of parts described below and illustrated in the accompanying drawing, in which—

Fig. 1 is an elevation view of a collar for a garment;

Fig. 2 is a sectional view thereof, somewhat enlarged, taken in about the plane 2—2 of Fig. 1;

Fig. 3 is a fragmentary, sectional view, somewhat enlarged and similar to Fig. 2 but in perspective, showing the collar in overfolded position;

Fig. 4 illustrates a garment with the collar thereof, embodying my invention, upturned to provide protection to the ears of the wearer; and

Fig. 5 is a view somewhat similar to Fig. 4 but showing the collar turned down.

I have illustrated in the drawing and in the following will describe the preferred embodiment of my invention.

Referring to the drawing and first to Figs. 1 through 3, I indicates generally a collar for a garment or overcoat which is adapted to be fastened or stitched to the garment in the usual manner. The collar comprises an outer thickness of material 2 which substantially conforms in size and shape to the finished collar 1. The strip of material 2 is indicated as the outer thickness since it lies on the outer side of the collar when the collar is overfolded in the position illustrated in

Figs. 3 and 5. To the outer thickness of material 2 is stitched an inner thickness of material 3 which, generally speaking, conforms in size and shape to the outer thickness of material 2 but which is cut away as indicated at 4 and along preferably a curvilinear line such as that indicated at the edge 5. The outer and inner thicknesses of material 2 and 3 are in-folded and stitched together along their side edges and along the free edge of the collar or the edge thereof opposite to that fastened to the body of the garment as by the line of stitching indicated at 6.

In accordance with my invention, I provide a flap 7 which is preferably but not necessarily formed from the same material as that from which the outer and inner thicknesses of material are cut. In practice, these thicknesses of material 2 and 3 and the flap 7 are preferably blanked out as separate pieces and thereafter stitched together although they may be formed integrally or the flap may be an integral part of the outer thickness of material 2.

In the embodiment illustrated, the flap 7 is stitched to the outer thickness of material 2 and along the free edge of the collar by the row of stitching 8. The edges 9 of flap 7 when bound or otherwise finished off are preferably complementary to the edge 5 of the inner thickness of material 3 which likewise may be bound or finished in any desired manner and the edges 9 of flap 7 preferably lie substantially adjacent and inter-fitted with the edge 5 of the material 3.

With the foregoing arrangement, the flap 7 may lie adjacent and substantially flat against the inside of the outer thickness of material 2 and within the cut-out portion 4 of the inner thickness of material 3 as shown in Fig. 1 to provide a collar of substantially uniform thickness throughout. In other words, the flap 7 is inlaid in and forms a part of the inner thickness of material 3, but is adapted to be upturned as illustrated in Fig. 4 and it will be noted that the end portions of the flap, being of substantially greater width than the central portion thereof, will be positioned when upturned to overlie the ears of the wearer of the garment. The central zone of the flap may be of reduced width as illustrated to provide freedom of movement of the head when the ears are covered by the flap. The collar, of course, is adapted to be fastened adjacent the edge 10 thereof to the body 11 of the garment.

Preferably, a band of material indicated at 12 is fastened at its opposite ends adjacent the ends of the flap 7 as illustrated. This band may be of elastic or other suitable material and may com-

prise tapes fastened together by means of a buckle which affords adjustment of the length of the band.

Furthermore, fastening means such as snap fasteners are preferably provided as indicated in dotted lines at 13 in Fig. 1. The co-operable parts of these fasteners may be fastened respectively to the end portions of the flap 7 and the outer thickness of material 2. In addition, I may provide a fastening means such as a snap fastener indicated in dotted lines at 14 in Fig. 1, the co-operable parts of which are respectively fastened to the outer and inner thicknesses of material 2 and 3. These fasteners are preferably so secured to the fabric of the collar that the fasteners or securing means therefor are not visible on the opposite side of the fabric. Furthermore, it will be understood that buttons and any suitable fastening means may be employed.

Ordinarily, when the flap 7 lies adjacent the outer thickness of material 2, the band 12 is folded therebetween and arranged beneath the central portion of the inner thickness of material 3. When so arranged, the parts may be fastened together by means of the fastening devices 13 and 14. However, when it is desirable to protect the ears, the collar may be upturned, the snap fasteners un-snapped and the flap 7 upturned to extend above the outer thickness 2 of the collar. The band 12 may then be adjusted to engage the head and hold the flap in position overlying the ears.

It will be noted that when the parts of the collar occupy the positions illustrated in Fig. 1, the collar may be neatly overfolded as illustrated in Fig. 5 and, being of substantially uniform thickness throughout, may be worn with the same comfort and neatness in appearance as any ordinary collar.

Furthermore, it is pointed out that the quantity of material used in making a collar embodying my present invention may be substantially the same as that employed in making ordinary collars.

My collar is particularly adapted to be embodied in work jackets, mackinaw coats and the like. The band serves to uphold both the flap over the ears and the collar as a whole snugly about the neck and the band when so engaging the head does not interfere with the hat which is worn thereover. In fact, any kind of head gear can be worn with my collar.

Additionally, it is to be noted that my collar is simple in construction and may be economically fabricated.

While I have described my invention in its preferred embodiments, it is to be understood that the words which I have used are words of description rather than of limitation. Hence, changes within the purview of the appended claims may be made without departing from the true scope and spirit of my invention in its broader aspects.

What I claim is:

1. In a garment, a collar fastened to said garment and adapted to be overfolded or raised to an upstanding position about the neck of a wearer of said garment, said collar comprising an outer thickness of material, a flap of less length than said outer thickness stitched thereto along the free edge of said collar and being adapted to be folded flat against the inner side of said outer thickness of material whereby to be concealed when the collar is overfolded and to be extended in upstanding position to overlie the ears of the

wearer, the ends of said flap being inwardly spaced from the ends of said collar and outer thickness of material, and an inner thickness of material arranged adjacent and underlying the inner side of said outer thickness of material and being substantially coextensive therewith but cut out to lie about and adjacent said flap when said flap lies adjacent said outer thickness; said inner thickness of material being stitched to said outer thickness of material along the ends of said collar and along the free edge of said collar substantially to the flap, and said flap and inner thickness of material being of like thickness whereby to provide a collar of substantially uniform thickness throughout.

2. In a garment, a collar fastened to said garment and adapted to be overfolded or raised to an upstanding position about the neck of a wearer of said garment, said collar comprising an outer thickness of material, a flap of less length than said outer thickness stitched thereto along the free edge of said collar and being adapted to be folded flat against the inner side of said outer thickness of material whereby to be concealed when the collar is overfolded, and said flap being of appreciably less width in the central portion thereof than at the end portions whereby to provide end flap portions adapted to overlie the ears of the wearer when extended in upstanding position and an intermediate flap portion adapted to upstand only slightly above the outer thickness of material, the ends of said flap being inwardly spaced from the ends of said collar and outer thickness of material, and an inner thickness of material arranged adjacent and underlying said outer thickness of material; said inner thickness of material and said flap being disposed side by side and substantially adjacent each other and each adjacent said outer thickness of material, and the adjacent edges of said flap and inner thickness being substantially complementary in shape; said inner thickness of material being stitched to said outer thickness of material along the ends of said collar and along the free edge of said collar substantially to the flap, and said flap and inner thickness of material being of like thickness whereby said collar is substantially of uniform thickness throughout.

3. In a garment, a collar fastened to said garment and adapted to be overfolded or raised to an upstanding position about the neck of a wearer of said garment, said collar comprising an outer thickness of material, means forming a pair of flaps adapted to overlie the ears respectively of the wearer of the garment, said flaps being disposed adjacent but spaced from each end of said outer thickness of material and being stitched thereto along the free edge of said collar and said flaps being adapted to be folded flat against the inner side of said outer thickness of material whereby to be concealed when the collar is overfolded and to be extended in upstanding position to overlie the ears of the wearer, an inner thickness of material arranged adjacent and underlying the inner side of said outer thickness of material and being substantially coextensive therewith but cut out in the zones of said flaps whereby said flaps when folded flat may lie against the inner side of said outer thickness of material; said inner thickness of material being stitched to said outer thickness of material along the ends of said collar and along the free edge of said collar substantially to the flaps, the edges of said inner thickness at said cut-out portions being arranged to lie adjacent said flaps when

folded flat and said flaps and inner thickness of material being of like thickness whereby to provide a collar of substantially uniform thickness throughout, and a band fastened to said flaps and adapted to engage the head of the wearer of the garment and uphold said flaps.

4. A garment collar comprising inner and outer thicknesses of material secured together to form a collar structure adapted to be overfolded with

said outer thickness of material on the outside of said collar, or raised to an upstanding position about the neck of a wearer of said garment with said inner thickness of material exposed; and ear flaps normally inlaid in and forming part of said inner thickness of material but adapted to be raised to overlie the ears of the wearer when said collar is in raised position.

HARRY MILLER.
